UNITED STATES PATENT OFFICE.

CLARENCE E. FERGUSON, OF PORTLAND, OREGON.

SAFETY CIGARETTE HOLDER.

Application filed August 27, 1925. Serial No. 52,791.

This invention relates to improvements in smokers' articles, and particularly to holders for cigarettes.

The object of my invention is the provision of a cigarette holder of simple and economical construction wherein the cigarette is enclosed while burning so that it is guarded from the wind and accidental loss or dislodgement and wherein the ashes are retained while the cigarette is being smoked and until a convenient place is found for their reception.

A still further object of the invention is the provision of an apertured closure for the outer end of the device whereby the cigarette-receiving chamber may be closed to the entrance of air and the combustion of the cigarette may be stopped at any time.

Other objects and advantages of my invention, and objects relating to details of construction and arrangement of parts thereof, will be fully apparent in the course of the detailed description to follow.

In the accompanying drawings, illustrating by way of example one form in which my invention may be embodied:

Figure 1 is a view in side elevation of an embodiment of my invention.

Fig. 2 is a view in longitudinal section of the same.

Fig. 3 is a view in side elevation of an element of the invention, detached.

Fig. 4 is a view similar to Fig. 3 showing the closure-cap thereof in open condition.

Fig. 5 is a view in cross section on line 5—5 of Fig. 1.

Fig. 6 is an end view of the device.

Fig. 7 is a detached view in side elevation of the closure-cap element of the invention.

Referring to said views, the reference numeral 1 indicates the mouth-piece element of my invention which is in general similar to the usual cigarette-holder, being formed with a cigarette-receiving recess 2 and a draft-channel 3 of the usual form. The end of the mouth-piece having the recess 2 is formed with a circular hub 5 terminating at its inner portion in a shoulder 6.

A tubular barrel 7 of cylindrical exterior conforming in size and shape with the mouth-piece is formed with an interior bore 8 adapted to be slipped upon and secured by friction upon the hub 5 of the mouth-piece. Said interior bore is of dimensions to receive

a cigarette in axial alignment therein with 55 an annular space thereabout for clearance.

A metal band 9 is secured to the outer extremity of said barrel having a closure-cap 10 hingedly secured thereto that will remain closed by friction when in use and may 60 be opened upon occasion to admit of the removal of ashes from the interior bore of the barrel. Said cap is formed with a plurality of ventilating apertures 11 arranged in groups which apertures may be closed by a 65 pivotally mounted shutter 12.

Upon one side of said bore a groove 13 is formed wherein the ashes falling from the burning cigarette may be collected until they are emptied after the cigarette is consumed.

In operation, the cigarette is placed in the recess 2 in the usual manner and when lighted the barrel 7 is placed thereover and secured upon the hub 5 so that the mouth-piece 75 and barrel become a single unit and with the groove 13 positioned upon the underside.

The smoker then smokes the cigarette in the usual manner with the apertures 11 open to admit air. The ashes will drop off into 80 the bottom of the bore 8 and into the groove 13 and thereby will not come into contact with the cigarette as they collect. After the cigarette has been smoked sufficiently the barrel may be removed from the mouth-piece to 85 admit of the cigarette-stub being removed and the ashes being emptied; or if this is not convenient at the time the shutter 12 may be closed over the apertures 11 whereupon the fire of the cigarette will go out and cease 90 smoking so that no fumes will escape from the barrel and the stub and ashes may be removed at a more opportune time.

The advantages other than those indicated above that reside in the use of my invention 95 may be briefly summed up in stating that it is a safeguard against the frequent setting of fires from accidentally falling cigarette stubs; it prevents the too rapid burning of the cigarette when smoked in a windy place 100 and the blowing of sparks therefrom; and it prevents the scattering of ashes generally upon a person's clothing and where a suitable ash-receptacle is not available.

While I have described my invention with some considerable detail, I do not intend to confine myself to the precise construction shown and described, as, obviously, modifica-

tion in construction within the spirit of the invention and the scope of the claims may be made within the protection sought.

Having described my invention, what I claim as my invention is:—

1. A safety cigarette holder, consisting in a mouth-piece provided with means for securing a cigarette therein, and a cylindrical barrel adapted to be secured upon the end 10 of said mouth-piece within which the cigarette may extend in axial alignment, said barrel having a longitudinally disposed groove upon one side to receive ashes dropped from a cigarette.

2. A safety cigarette holder, consisting in a 15 mouth-piece having a cylindrical hub at one end, a tubular barrel adapted to be secured at one end upon said hub to receive a cigarette in axial alignment therein that is secured in said mouth-piece, said barrel having 20 a longitudinally disposed groove upon one side to receive ashes from a burning cigarette, a closure-cap hingedly connected to the end of the barrel provided with a plurality of ventilating apertures, and a shutter on 25 said cap arranged to close said apertures.

CLARENCE E. FERGUSON.
